UNITED STATES PATENT OFFICE.

PETER WELIN, OF WORCESTER, MASSACHUSETTS, ASSIGNOR TO THE AEOLIAN COMPANY, OF MERIDEN, CONNECTICUT.

MECHANICAL MUSICAL INSTRUMENT.

SPECIFICATION forming part of Letters Patent No. 683,825, dated October 1, 1901.

Application filed February 12, 1901. Serial No. 47,022. (No model.)

To all whom it may concern:

Be it known that I, PETER WELIN, of Worcester, in the county of Worcester and State of Massachusetts, have invented certain 5 new and useful Improvements in Mechanical Musical Instruments, of which the following is a full, clear, and exact description.

This invention relates to certain new and useful improvements in mechanical musical 10 instruments, more particularly to pianolas or other mechanical musical instruments operated by a perforated musical sheet; and to this end the invention consists in the novel combination and arrangement of parts hereinafter more specifically described, illustrated 15 in the accompanying drawings, and particularly pointed out in the claims hereunto appended.

Referring to the drawings, Figure 1 is a detail front view of a portion of a pianola, showing the take-up roll, perforated music-sheet in place, some of the driving mechanism of the instrument, and with the present invention in front view. Fig. 2 is a detail end view 25 of part of the driving mechanism. Fig. 3 is a detail transverse vertical cross-section on line 3 3, Fig. 1. Fig. 4 is a plan view of the under side, showing some of the operating parts of the present invention. Fig. 5 is a 30 plan view in detail of parts of the invention for operation on the music-roll more particularly.

In the drawings, A represents the take-up roll arranged to turn in two upright arms B C 35 of a horizontal rock bar or board D, pivoted at each end at a to the uprights E F, respectively, of the framework and at the forward part of the bar D, as shown in Fig. 3 more particularly, so that the uprights, with the 40 take-up roll, will by their gravity swing backward within certain limits for the purpose to be described.

G is a shaft turning in bearings in the upright F and a bracket K, having a pinion-gear H on its end, which is in line with a gear J, secured to the take-up roll, so that when it is 45 swung forward on the pivots a the gear J will engage the gear H for the turning of the take-up roll as the shaft G is turned. The shaft 50 G has a sprocket-wheel L, which is arranged to have engaged therewith a sprocket-chain,

in turn engaging with the driving-shaft of the motor, but not shown. M is another sprocket-wheel on the shaft G, having a sprocket-chain N, which engages with a sprocket-wheel P on 55 a loose sleeve Q on a shaft R, turning in a bracket S and a bearing in the upright F, to which shaft is connected the music-roll T. When the sleeve is moved to the right, Fig. 1, it engages, by a pin d, with a pin e of a collar f, secured to the shaft R, by which as the sleeve is turned the shaft will be turned, and with it the music-roll; but when the sleeve is moved to the left it will be free of its clutch connection with the shaft and not turn the 65 shaft with it.

U is a lever pivoted at g to the front of the framework and projecting up through an opening in the frame-board V and having connected to it a rod W, which by its other 70 end is connected to a right arm h of a rock-shaft Y, pivoted in bearings m n, and having another arm r near its upper end with a pin t, which engages with a circumferential groove u in the sleeve Q, so that by swinging the lever 75 U to the right into the position shown in Fig. 1 the rock-shaft Y is turned sufficiently for its arm r to move the sleeve to the left, as shown in Fig. 1, and thus disengage it from the music-roll shaft R, so it will not be operated, and by moving the lever to the left the rock-shaft is swung in the opposite direction and the sleeve moved to the right to engage, as described, with the music-roll shaft R for 80 it to be turned in the operation of the instrument. 85

Under the board V is a horizontal wire or rod A', disposed, respectively, in blocks V W, secured to the under side of the board, forming bearings in which the wire can rock or 90 turn. This wire A' has right-angular bends or offsets B', as shown more particularly in Fig. 1, and one end is bent forward, as at a', and then to the right, as at b', to be in position for such end b' to bear against the upper 95 side of a block or shoulder d', secured to the inner side of the lever U, so that as the lever is swung to the left, Fig. 1, it will press against the arm b' and, raising it, cause the wire A' to swing in its bearings for its bends 100 B' to move downward, and as the lever is moved to the right the wire will swing down

not only from its gravity, but from other means to be described.

Back of and near each end of the take-up roll is an arm C', extending down through 5 openings e' in the board V and pivoted at f' to the frame, the upper end of each arm having a friction-roll g' pivoted thereto and arranged to bear when desired against the take-up roll or upon the music-sheet as it is 10 being wound thereon, as shown more particularly in Fig. 3. The arm C' has a right-angular extension D' beyond its pivot under the board V and has a spiral spring E' bearing 15 on its upper side at its end and against the underside of the board, which acts to hold the extension D' down and thus the friction-roll g' against the take-up roll. The end of each extension D' of the arms C' is flattened for a seat for the spring and is disposed in a 20 bend B' of the wire, as shown more particularly in Figs. 1 and 3, so that as the wire is swung in the right direction the wire bends will move up and carry with them the extensions D' of the arms C' and, swinging them 25 back, will move their friction-rolls from bearing upon the take-up roll.

Pivoted at h', back of the music-roll shaft R, is an arm F', similar to the arm C', having a friction-roll m' in its upper end, which is in 30 position to bear when desired against a wheel G', secured to the music-roll shaft R, being held thereto by a spiral spring H', resting on the frame and pressing up against an arm n' of the arm F', as shown more particularly in 35 Fig. 2. On the upper end of the rock-shaft Y is an arm J', which is in position as the rock-shaft is turned to press against an extension r' of the arm F', which extension has its face at such an angle that the pressure of 40 the arm J' thereon will move the arm F' back for its friction-roll to be free and clear of the wheel on the music-roll shaft. This arm F', with its friction-roll, is to bear when desired against the wheel to create sufficient friction 45 thereon to control the movement of the music-roll as it is turned to unwind the music-sheet therefrom, so that the music-sheet will be unwound and delivered therefrom evenly, regularly, and sufficiently slow for its being 50 wound upon the take-up roll properly.

From one end of the rocking board D of the take-up-roll frame extends an arm K', which when the take-up roll is swung forward a notch t' in the edge of the lever engages 55 with the arm K' and locks the frame from movement.

In the operation of the instrument, the music-sheet being wound upon the music-roll and the roll placed in the instrument in the 60 usual manner, the outer end of the music-sheet is connected to the take-up roll. The lever U is moved to the right to engage the pinion-gear H with the take-up-roll gear J, while at the same time the rock-shaft Y is 65 turned, releasing the sleeve Q from engagement with the music-roll shaft R, so it is free to turn. The arm d' of the wire A' is released

from pressure upon it by the lever U as it is moved, which allows the springs E' to the arms D' to press them down and thus the 70 friction-rolls g' against the take-up roll, which forces the take-up roll forward by its frame D swinging on its pivots for the gear J to engage with the pinion-gear H of the shaft G. Also by the swinging of the rock-shaft y its 75 arm J' is moved from pressing upon the extension n' of the arm F', which allows its spring H' to act upon the arm to press its friction-roll m' against the music-roll-shaft wheel G' to create the necessary friction 80 thereon. The motor being now operated, the take-up roll is revolved, winding the music-sheet thereon, and as it is so wound the arms C' bear and press against the music-sheet on the take-up roll and cause it to lie evenly, 85 clearly, and smoothly, preventing any looseness of the music-sheet which might wrinkle or full upon the roll. Also the friction-arms F' bear upon the music-roll-shaft wheel and create sufficient friction thereon to prevent 90 the delivery of the music-sheet too fast to interfere with its proper wind upon the take-up roll. When it is desired to remove the music-roll from the instrument, the lever U is swung to the left, which swings the wire A' 95 for its bent portions B' to move upward and swing the arms C' so their friction-rolls are moved from pressure upon the music-sheet. The arm K' of the take-up-roll frame is released from its interlock with the lever U, 100 allowing the take-up roll to fall back, disengaging its gear J from the pinion-gear H, moving the sleeve Q to engage with the music-roll shaft, moving the arm F' for its friction-roll m' to be moved from contact 105 with the wheel G' on the music-roll shaft R, when the motor will turn the music-roll shaft and rewind the music sheet thereon, so that the music-roll and its music-sheet can be removed from the instrument and another music-roll with its music-sheet inserted therein. 110

In lieu of the spring-arm F' bearing upon the wheel of the music-roll shaft it can be arranged to bear directly upon the roll by having the roll extend sufficiently beyond the 115 music-sheet at one end.

The frame D, carrying the take-up roll, is arranged to be adjusted longitudinally in its support for the purpose of adjusting the take-up roll in relation to winding the music-sheet 120 thereon—as, for instance, if the music-sheet should run to one side or the other, causing the music-sheet to be wound upon the take-up roll improperly, the take-up-roll frame can be moved correspondingly and secured, and 125 thus adjust the take-up roll in position for proper winding of the music-sheet thereon. This arrangement is shown in Fig. 1. In each upright E F, in which are the bearings for the frame D, there is a screw L', each in the axial 130 line of the pivot a of the frame and arranged to screw against the outer end of the pivot, and by turning these screws in or out the frame can be adjusted in its bearings and se-

cured in such adjustment by the screws so the take-up roll will receive the music-sheet properly in winding thereon.

Having thus described my invention, what I claim is—

1. In a pianola or other mechanical musical instrument operated by a perforated music-sheet, a take-up roll, a perforated music-sheet arranged to be wound thereon, a pivoted arm having at one end a roll or wheel arranged to bear upon the take-up roll and the music-sheet being wound thereon, a spring to the arm, a wire pivoted to a support, a bent portion to engage with and operate the arm and an arm 15 to the wire and a lever arranged to operate the wire arm.
2. In combination a frame pivoted at each end in a bearing, a music or take-up roll for a perforated music-sheet pivoted to the frame, 20 a screw to each frame-pivot in axial line therewith so the frame can be adjusted longitudinally in its bearings.
3. In a pianola or other mechanical musical

instrument, a music-roll, a perforated music-sheet wound thereon and arranged to be unwound therefrom and rewound thereon, a take-up roll onto which the perforated music-sheet is wound from the music-roll, means constructed and arranged to bear against each of said rolls as a music-sheet is wound on the 25 take-up roll and unwound from the music-roll to create friction for the purpose specified, mechanism constructed and arranged to connect to and disconnect from the music and the take-up rolls the winding and rewinding 30 mechanism, in combination with a lever for operation of both frictional mechanisms and the connecting and disconnecting winding and rewinding mechanism.

In testimony whereof I have hereunto set 40 my hand in the presence of two subscribing witnesses.

PETER WELIN.
